(57) **CLAIM**

The industrial design for the golf tee sharpener and divot repair device, as shown and described.

DESCRIPTION

FIG. 1 is a first perspective view of the device;

FIG. 2 is a second perspective view of the device;

FIG. 3 is a top view of the device;

FIG. 4 is a right side view of the device;

FIG. 5 is a front view of the device; and,

FIG. 6 is a rear view of the device.

The bottom view is omitted from the Drawings as the device has a bottom that is flat and that is devoid of surface ornamentation. The left side view is omitted from the Drawings as it is a mirror image of the right side view of the device.
